UNITED STATES PATENT OFFICE.

KATE L. BARTHOLOMEW, OF PORTLAND, OREGON.

DESIGN FOR A CAP.

58,303.

Specification for Design.

Patented July 12, 1921.

Application filed April 29, 1920. Serial No. 377,717. Term of patent 3½ years.

To all whom it may concern:

Be it known that I, KATE L. BARTHOLOMEW, a citizen of the United States, residing at Portland, county of Multnomah, and State of Oregon, have invented a new, original, and ornamental Design for Caps, of which the following is a specification, reference being had to the accompanying drawing, forming part thereof.

In the drawings, Figure 1 shows a top plan view, and Fig. 2 a side elevation of a cap showing my new design.

The essential feature of my design consists of a plurality of radially disposed segmental disks of different colors, the center from which said disks radiate, being covered by a circular disk.

I claim:

The ornamental design for a cap as shown.

KATE L. BARTHOLOMEW.
